INTERLOCKING SHINGLE

Blaney H. Howle, Sr., Florence, S. C., assignor of
one-half to David Charles Shaw, Jr., Florence,
S. C.

Application August 24, 1939, Serial No. 291,733

3 Claims. (Cl. 108—7)

My invention relates to interlocking shingles and the roofing produced thereby.

An important object of the invention is to provide a shingle carrying an interlocking element permanently attached thereto and which serves as a gauge for locating and spacing the adjacent companion shingle in the same line.

A further object of the invention is to provide interlocking shingles which are securely held in position upon a roof against improper displacement, but are capable of slight relative movements due to expansion and contraction.

A further object of the invention is to provide a roofing which is attractive in appearance, durable, and one which may be readily and cheaply laid.

Other objects and advantages of the invention will be apparent during the course of the following description.

20 In the accompanying drawing forming a part of this application and in which like numerals are employed to designate like parts throughout the same,

Figure 1 is a plan view of the shingles embodying my invention, assembled to produce a roof section,

Figure 2 is a perspective view of one of the shingles,

Figure 3 is a detailed section taken on line 30 3—3 Figure 1, and,

Figure 4 is a similar view taken on line 4—4 of Figure 1.

In the drawing, wherein for the purpose of illustration is shown a preferred embodiment of my invention, the numeral 10 designates a flexible shingle. This is preferably a composition shingle although the same may be formed of metal or other material. The shingle is a parallelogram and is preferably square. The lower corner of the shingle is cut off providing a horizontal edge 11, and its oppositely arranged side corners are also cut off, providing vertical edges 12 and 13, while the upper corner of the shingle is not cut off but continues to a point. Permanently secured to and preferably formed integral with the shingle 10 at the vertical edge 13 is a locking device comprising a horizontal strip 14, having a vertical edge 15. Formed upon the lower horizontal edge of the strip 14 is a shank 16 having a laterally extending tongue 17. The shank 16 is straight and has a sufficient length, such as approximately $\frac{1}{2}$ " or more, to permit the slight movement of creeping of the companion shingle interlocked therewith, due to changes in temperature or the like. The shingle 10 is provided

adjacent to its lower horizontal edge 11 with a U-shaped slit 18, disposed at 90 degrees from the locking device 14. Tongue 17 is adapted to be inserted through the slit 18 and will engage over the companion shingle, while the shank 16 will be held within this slit.

In assembling the shingles to produce a roof, a lowermost horizontal row of shingles is provided, by arranging the shingles in the row, with the edges 11 lowermost. The strip 14 of one shingle contacts with the vertical edge 12 of the adjacent companion shingle and serves as a gauge for arranging and spacing the shingles. The shingles are nailed down, as shown at 19, 20 and 21. The nail 19 passes through the shingle adjacent to the strip 14 integral therewith, nail 20 passes through the strip 14 at its center while nail 21 passes through the adjacent companion shingle adjacent to its vertical edge 12. The shingles in the next upper horizontal row are now assembled, and the tongue 16 of the lower shingle is inserted through the slit 18 of the corresponding shingle in the next upper row, thereby locking down the lower end of the upper shingle, so that it is held down against curling or rising. The shingles in the upper row overlap the shingles in the next lower row, as shown. The shank 16 permits of a slight or limited movement of the adjacent shingle due to heat changes or the like. When the shingles are placed in position to form the roof they are in diamond formation. Each shingle has a square or rectangular body portion, and the opposed lower edges of each body portion converge downwardly while the upper opposed edges converge upwardly, forming upper and lower corners and intermediate corners. The strip 14 has its longitudinal axis horizontal, and the converging opposed upper and lower edges of the body portion are arranged oblique with respect to this longitudinal axis. The slit 18 is arranged at the lowermost corner of the body portion, and the slit is horizontal, and the converging edges of the body portion are oblique with respect to the slit, and the ends of the slit are closed.

45 It is to be understood that the form of my invention herewith shown and described is to be taken as a preferred example of the same and that various changes in the shape, size, and arrangement of parts may be resorted to, without departing from the spirit of my invention, or the scope of the subjoined claims.

Having thus described my invention, what I claim is:

1. A roofing comprising a plurality of shingles 55

arranged in diamond formation, the shingles being disposed in horizontal rows, each shingle comprising a substantially rectangular body portion having opposed lower downwardly converging edges and opposed upper upwardly converging edges forming upper and lower corners and intermediate corners, each shingle having a strip permanently secured thereto at one intermediate corner, said strip having a laterally extending tongue, said strip having its longitudinal axis substantially horizontal and the opposed lower downwardly converging edges and the opposed upper upwardly converging edges being arranged oblique with respect to the longitudinal axis of the strip, each body portion being provided adjacent to its lower corner with an opening, the laterally extending tongue of the strip carried by one shingle in the lower row engaging within the opening at the lower corner of the shingle in the next upper horizontal row.

2. In a roofing, a shingle having a body portion which is substantially rectangular, said body portion having opposed lower downwardly converging edges and opposed upper upwardly con-

verging edges forming upper and lower corners and intermediate corners, the shingle having a strip permanently secured thereto at one corner and projecting beyond the corner, said strip having a downwardly extending tongue, said strip having its longitudinal axis substantially horizontal and the opposed converging edges of the body portion being diagonal with respect to the longitudinal axis of the strip, the body portion being provided adjacent to its lower corner with a slit.

3. In a roofing, a substantially square shingle having a body portion provided with opposed lower downwardly converging edges and opposed upper upwardly converging edges forming upper and lower corners and intermediate corners, the shingle having a substantially horizontal strip formed integral therewith at one intermediate corner, the converging edges of the body portion being diagonal with relation to the longitudinal axis of the strip, said body portion being provided adjacent to its lower corner with a slit which is substantially horizontal and has its ends closed.
